FLOW RESTRICTING DISK FOR A VALVE OR SIMILAR ARTICLE

Richard E. Self, 3221 Brimhall Drive,
Los Alamitos, Calif. 90720

Filed Oct. 21, 1968, Ser. No. 14,091

Term of patent 14 years

Int. Cl. D23—01

U.S. Cl. D23—27

FIG. 1 is a plan view of a flow restricting disk for a valve or similar article, showing my new design; and

FIG. 2 is a fragmentary sectional view thereof taken substantially along the line II—II of FIG. 1.

I claim:

The ornamental design for a flow restricting disk for a valve or similar article, as shown.
